UNITED STATES PATENT OFFICE.

JOHN C. PASHBY, OF LYNN, MASSACHUSETTS.

NAILING MACHINE.

Application filed July 18, 1921. Serial No. 485,526.

To all whom it may concern:

Be it known that I, JOHN C. PASHBY, a citizen of the United States, residing in Lynn, in the county of Essex and State of Massachusetts, have invented an Improvement in Nailing Machines, of which the following description, in connection with the accompanying drawings, is a specification, like characters on the drawings representing like parts.

This invention relates to a nailing machine and is herein shown as embodied in a machine for nailing together the lifts of a heel for boots and shoes preparatory to attaching the same to the boot or shoe.

The present invention has for its object to provide a nailing machine of the character described, with which the nails may be driven into the lifts at an acute angle to the breast portion of the lifts, so that the upper or pointed ends of the nail may be directed away from the breast of the rough or unfinished heel, and so that in case the pointed end of the nail is bent or deflected from a straight path and directed toward the breast portion of the heel, sufficient space is afforded for material deflection or bending of the free or pointed end of the nail without danger of bringing the pointed end of the nail near enough to the breast portion to be engaged by the breast knife employed in trimming the breast portion of the heel; when the latter is finished or trimmed at its breast portion.

To this end, the nailing machine is provided with a throat for the nail driver, which throat in its operative position is inclined with relation to the bed of the machine upon which the heel lifts are assembled, and said throat is preferably pivoted and provided with a curved upper surface, whose center is the pivot of the throat. Provision is made for securing the throat in different angular positions. Provision is also made for operating the driver in all positions of the throat, as will be described.

The throat may and preferably will be constructed to prevent leakage of paste down through it, as will be described.

The machine may and preferably will be provided with an adjustable and yielding clamp or holding device for the assembled heel lifts, as will be described.

These and other features of this invention will be pointed out in the claims at the end of the specification. 55

Fig. 1 is an elevation of a nailing machine embodying this invention.

Fig. 2, a detail in elevation of the throat 60 shown in Fig. 1.

Fig. 3, a detail showing the throat in an inclined position.

Fig. 4, a detail showing the method of 65 mounting the throat.

Figs. 5 and 6, details of the yielding side clamps for the heel lifts.

Figs. 7 and 8, details of the top clamp for the heel lifts, and

Fig. 9, a section of a portion of the bed 70 with the throat omitted.

Referring to the drawings, *a* represents the table or bed of the machine, which is supported upon suitable standards or legs *b*. The bed *a* is provided on its underside, 75 as herein shown, with a curved recess 10, which is struck from a center 12 and extends through the bed to form an elongated slot 13 therein, through which extends the curved upper surface 14 of a throat 15, see Figs. 2, 3 and 4, for a driver 16. The throat 15 in the present instance is mounted to turn or pivot upon center screws 17 carried by lugs 18 depending from the bed plate *a*, and extended through guide plates 19 depending 80 from the bed plate and between which the throat 15 is confined. The throat 15 is thus capable of being turned on its pivots 17 from a substantially vertical position shown in Figs. 1 and 2 into different inclined positions, one of which is shown in Fig. 3, so as to present the bore 20 of the throat either in a vertical or an inclined position 85 with relation to the upper surface of the bed plate, and to a series of heel lifts 21 assembled upon the bed plate *a* above the slot 13 therein. The bore 20 of the throat 15 has extended up into it the driver 16 for the nails 22 employed to fasten the superimposed heel lifts together to form an unfinished or rough heel which is to be applied to the boot or shoe, not shown, and finished in a manner now commonly practiced in shoe factories. The driver 16 is 90 extended into the bore 20 of the throat 15 and is reciprocated therein to drive a nail at each reciprocation of the driver.

In the present instance the driver 16 is at- 95

tached to a reciprocating carrier, shown as a bar or rod 23 provided with rack teeth 24, which are engaged with a gear 25, also engaged with the teeth 26 of a second rack 5 bar 27, which is connected by a link 28 with a lever 29, pivoted at 30 to an arm 31 attached to a frame or support 32 for the rack bars 23, 27 and gear 25. The lever 29 is connected by a link 34 with a foot treadle 35 pivoted at 36 to a suitable support 37. The frame 32 is suspended from the pivoted throat, which is effected, as shown, by providing the throat 15 with depending arms 38 which are internally threaded at their lower ends to be engaged by external threads on a nut 39 having internal threads which engage a threaded hollow boss 40, attached to the top of the frame or support 32.

20 It will thus be seen that the support 32 and the mechanism carried thereby are operatively connected with the throat, and the latter may be turned to present its bore into the desired inclined position with relation to the bed plate, and when thus positioned the throat of the support 32 may be fixed in the selected position by means of a nut 41 extended through the slotted curve 42 in the bar or arm 43 attached to one of the legs b.

By setting up the nut 41 the frame 32 and the throat are fastened in their adjusted inclined position.

When the throat has been adjusted into the desired inclined position with relation to the heel lifts, the operator depresses the treadle 35 and effects movement of the driver 16 by means of the rack bars 27, 28, and gear 25, to cause the driver to drive the nail 22 in the throat out therefrom into the superimposed heel lifts 21 after the manner represented in Fig. 3.

The heel lifts are pasted together and assembled upon the bed plate over the opening 13, and are firmly held on the bed plate, which may be effected in any suitable manner, and in the present instance is shown a preferred construction of means for clamping the lifts in position on the bed plate.

50 To this end, devices are provided for engaging the breast position, top and side and rear portions of the superimposed lifts. The device for engaging the breast portion is shown as an upright member 46 of a plate 47, which is fastened by screws 48 to the bed plate a. The top clamp is shown as a plate 50 attached to a plunger or hollow spindle 51 extended up through a hollow boss or cylinder 52, see Fig. 7, attached by an arm 53 to a hub 54 mounted to turn on a stud or pin 55 erected upon the bed plate a. The plunger or spindle 51 is normally elevated by a spring 56 which bears at its upper end against a head 58 on the spindle 65 and at its lower end against a collar 59 fixed

in the lower end of the hollow boss or cylinder 52 by a set screw 60. The head 58 of the spindle carries a roller 160 which is engaged by a cam lever 61 mounted on a pivot pin 62 between arms 63 extended from the boss 52. Normally the lever 61 is extended vertically as shown in Figs. 7 and 8 and the spring 56 elevates the clamping plate 50, but when the lever is turned into a horizontal position, the clamping plate 50 is lowered and firmly presses the heel lifts down onto the bed plate. The side and rear clamping devices are shown separately in Figs. 5 and 6 and each consists of an inclined strip or bar 65 suitably shaped to engage the heel lifts and a straight strip or bar 66.

The inclined bar or strip 65 is connected with one or more plungers 67 located in cylinders 68, which are carried by an inclined arm 69 on a bar 70 attached to the bed plate a. In the present instance three cylinders 68 are carried by the inclined arm 69 and each contains a spring 71, see Fig. 6, which bears against the plunger 67 and whose tension or pressure is regulated by a screw plug 72. The horizontal bar 70 contains a spring 73, which acts on a plunger 74 whose tension or pressure is regulated by the screw plug 75.

To prevent leakage of paste through the bore of the throat, the latter is provided at its lower end with a recess 76, see Fig. 3, preferably conical in form, which receives a conical projection 77 on a cap 78 screwed upon the throat, said cap and projection having a bore for the passage of the driver, and cooperating with a packing 80 of felt or other suitable material, which is pressed about the driver, see Fig. 3, sufficiently hard to effect a tight fit and prevent leakage of the paste down through the throat.

In Figs. 1 and 2, the throat 15 is arranged normal to the bed plate, and it will be seen that if the nail 22 should be driven into the heel lifts with the throat in this position, the nail may be driven in a straight path substantially parallel with the breast portion of the heel lifts, but is liable to have its free end bent or deflected toward the breast portion of the heel lifts as indicated by the dotted line 90, in which position, the deflected nail is brought into the path of the knife employed to finish the breast portion of the heel, which is highly objectionable, as the heels are ruined and the breeding knife damaged. In Fig. 3, the throat is inclined away from the breast portion of the heel lifts, and the nail 22, if it remains straight, is inclined away from the breast portion as represented in Fig. 3, and if the free end is bent or deflected toward the breast portion of the heel lifts, ample room is afforded for the free end of the nail to be deflected toward the breast portion of the

lifts without danger of being brought into the path of the knife employed to trim the breast portion of the heel. Furthermore, if the deflection takes place, it would be 5 more natural for the point to deflect toward the rear portion of the heel as indicated by the dotted line 91, in which event ample room is afforded for such deflection. The top clamping member 50 is capable of 10 being swung in the arc of a circle with the stud or pin 55 as a center, when it is desired to place the heel lifts in position to be nailed, and also when it is desired to remove the heel lifts after they have been 15 nailed together.

In the present instance the throat 15 is shown as pivoted so that it can be moved into different angular positions to enable different sizes of heels to be nailed on a 20 single machine, but it is not desired to limit the invention in this respect, for in cases where the same size of heels is being used, the throat may be fixed in a permanently inclined position with relation to the bed 25 and the breast of the lifts to be nailed.

I claim:

1. In a nailing machine of the character described, in combination, a bed provided with a curved recess in its under surface extended to the top surface thereof to form therein a slot, a throat having a curved upper surface conforming to the curvature of said recess, means for pivotally mounting said throat below said bed, to permit it to be moved into an inclined position, a nail driver movable in said throat, and mechanism movable with said throat for actuating said driver.

2. In a nailing machine of the character described, in combination, a pivoted driver throat, a driver cooperating therewith, mechanism for operating said driver, and a support for said mechanism connected with said throat to be supported thereby and to 45 move therewith.

3. In a nailing machine of the character described, in combination, a bed plate provided with an opening through it, means for positioning a plurality of heel lifts over said opening, a driver throat located below said bed plate and having its bore inclined at a sufficiently acute angle to the breast portion of said heel lifts, to prevent a nail driven from said throat into the heel lifts to be deflected to the breast surface thereof, a driver cooperating with said throat, and means for operating said driver to drive a nail into said heel lifts at an angle to the breast portion of the latter and with its

free end directed away from said breast portion.

4. In a nailing machine of the character described, in combination, a bed to support a plurality of heel lifts to be nailed, a driver throat cooperating with said bed and inclined at a sufficiently acute angle to the breast portion of the heel lifts to be nailed to prevent a nail driven from said throat into the heel lifts to be deflected to the breast surface thereof, a driver and means 65 for operating the latter.

5. In a nailing machine of the character described, in combination, a bed plate, a breast plate against which the breast portion of a plurality of heel lifts are positioned, clamping members to engage the sides and rear portion of the heel lifts and bodily movable independently of one another, yielding means for normally moving said clamping members into position to be 75 engaged by the heel lifts, and means for limiting the movement of said clamping members by said yielding means to initially position them with relation to said breast plate.

6. In a nailing machine of the character described, in combination, a bed plate, a breast plate erected upon said bed plate, a plurality of clamping members bodily movable independently of one another and co-operating with said breast plate for engaging a plurality of superimposed heel lifts and yielding means cooperating with said clamping members for forcing the breast portion of said heel lifts against said breast plate, means for limiting the movement of said clamping members by said yielding members, a top clamping member to engage the uppermost heel lift, and means for moving said top clamping member toward said 90 bed plate.

7. In a nailing machine of the character described, in combination, a bed plate, a breast plate erected upon said bed plate, a plurality of clamping members bodily movable independently of one another and co-operating with said breast plate for engaging a plurality of superimposed heel lifts, and yielding means co-operating with said clamping members for forcing the breast portion of said heel lifts against said breast plate, and means for limiting the movement of said clamping members by said yielding members.

In testimony whereof, I have signed my 115 name to this specification.

JOHN C. PASHBY.
